UNITED STATES PATENT OFFICE.

ALBERT LEROY CRITTENDEN, OF SHELLMAN, GEORGIA, ASSIGNOR OF
ONE-HALF TO F. REID CRITTENDEN, OF SHELLMAN, GEORGIA.

WRENCH.

No. 805,946.

Specification of Letters Patent.

Patented Nov. 28, 1905.

Application filed August 26, 1905. Serial No. 275,925.

To all whom it may concern:

Be it known that I, ALBERT LEROY CRITTENDEN, a citizen of the United States, residing at Shellman, in the county of Randolph and State of Georgia, have invented certain new and useful Improvements in Wrenches, of which the following is a specification.

This invention relates to wrenches.

One object is to provide a wrench embodying such characteristics as to render it efficient for use either as a nut or pipe wrench.

Another object resides in the provision of an exceedingly simple, inexpensive, durable, and efficient nut or pipe wrench.

A still further object of the invention is to provide a device of the character stated wherein the parts thereof may be quickly assembled or readily disassembled.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view of my improved wrench. Fig. 2 is a side elevation illustrating the same applied for the manipulation of a nut, parts being shown in section. Fig. 3 is a transverse sectional view on the line *a a* of Fig. 1. Fig. 4 is a longitudinal sectional view of the strap. Fig. 5 is a side elevation, partly in section, of a modified form of the invention. Fig. 6 is a detail view of the shank.

Referring now more particularly to the accompanying drawings, the reference character 1 designates a stock having formed integrally therewith at one end the inner jaw 2. It will be observed that this jaw 2 extends upon both sides of the stock 1 and has its lower end reduced, as at 3, with its under face provided with teeth 4 for mesh with the teeth 5 of a shank 6. The front face of the jaw 2 above the reduced portion 3 thereof is also provided with teeth 7, designed for mesh with the teeth 8 of an outer jaw 9, which is formed integrally at one end of the aforesaid shank 6. The teeth 8 of the outer jaw 9 terminate short of the upper edge of

the shank 6, forming a flat surface 10 for engagement with the flat front face of the reduced portion 3 of the inner jaw 2. It will be observed that the inner toothed and smooth or flat face of the outer jaw tapers toward the inner jaw.

The stock 1 and the shank 6 are coupled together by means of a strap 11, which is provided with oppositely-disposed openings 12 and 13, the opening 12 receiving the stock 1 and the opening 13 receiving the shank 6. The stock 1 is pivotally mounted in the opening 12 of the strap 11 by means of a suitable pivot-pin 14, and the teeth 4 of the reduced portion 3 of the jaw 2 of the stock 1 are held normally out of engagement with the teeth 5, formed in the upper face of the shank 6, by means of a suitable flat spring 15, secured at one end, by means of a suitable fastener 16, to the upper face of the stock 1, with its opposite end directed forwardly and free for engagement with the beveled side 17 of the opening 12. By reason of the beveled portion 17 of the opening 12 the stock 1 may be moved upon its pivot 14 to present the teeth 4 of the reduced portion 3 of the inner jaw to the teeth 5 of the shank 6. The shank 6 has a longitudinal bore 18 opening through its inner end for the reception of a helical spring 19, which is prevented from accidentally falling out of the bore 18 by means of a suitable screw 20, fitted in the screw-threaded end 21 of the bore 19 of the shank 6. Obviously by reason of this screw 20 the spring 19 may be readily removed from the bore 18 for any purpose desired. The purpose of this spring 19 is to force the strap 11, and consequently the stock 1 and its jaw, toward the outer jaw 9 of the shank 6, and thereby normally hold the inner and outer jaws together or tightly upon the nut or pipe for manipulation of the latter two elements. In order that the spring 19 may perform the function just stated, I form a slot 22 in one side of the shank 6. This slot is arranged longitudinally of the shank and communicates with the aforesaid bore 18 of the shank, so that the projection 23, which is engaged with the inner face of one side of the opening 13 of the strap, may project through the said slot 22 into the said bore 18 for engagement with one end of the aforesaid helical spring 19 to compress the latter upon movement by one's hand or otherwise of the strap from the outer jaw 9 of the

shank. Obviously, therefore, the said spring 19, being under tension by such movement of the strap, will as soon as the strap 11 is released by the hand or engaged with a nut or pipe immediately force the strap 11 toward the outer jaw 9, and consequently carry with it the inner jaw 2 of the stock 1.

To prevent the strap 11 being accidentally disengaged from the shank, I provide a suitable stop 24, which is formed upon the under face of the shank 6 at the extreme inner end of the latter.

From the foregoing it will be seen that the inner and outer jaws of the stock and shank, respectively, are held normally in engagement with each other or upon a nut or pipe through the instrumentality of the helical spring 19, confined within the shank. It will be apparent also that the device may be readily used as a nut or pipe wrench and that the teeth of the inner jaw are held normally out of engagement with the teeth of the shank through the medium of the flat spring 5, secured to the stock.

In Figs. 5 and 6, inclusive, there is shown a modified form of my invention. With the exception of a few minor features this modified form of the invention is the same as that first described. In other words, the stock 1' is pivoted in the opening 12' of the strap 11', there being a flat spring 15' secured to the stock 1 and projecting into the said opening 12' for the same purpose as the aforesaid spring 15. However, in this modified form the inner jaw 2' is provided upon its inner beveled face with a recess 25, adapted to embrace the inner end of the stock 1 and be removably secured thereto by means of a suitable fastener 26. Each of the inner jaws has its inner face beveled, as shown in the drawings, so as to permit the proper engagement of the teeth of each inner jaw with the teeth upon the adjacent face of the shank 6 and 6'. Another difference in this modified form is that instead of forming the slot 22' in one side of the shank 6' I form the slot 22' in the back of the shank 6' and provide a projection 23' upon one inner face of the opening 13' of the strap 11' for engagement in the slot 22'. This slot 22', as in the other form of the in-

vention, communicates with the bore 18' for coöperation with the helical spring 19'. Except for the differences just outlined both forms of the invention are substantially alike, and therefore it is believed that further description is entirely unnecessary.

What is claimed is—

1. A wrench comprising a stock having a jaw at one end, a shank having a jaw at one end for coöperation with the jaw of the stock, a strap having openings therethrough for the reception of the stock and the shank, the shank having a longitudinal bore and a longitudinal slot in communication with each other, a helical spring removably arranged within the bore of the shank, a projection carried by the said strap and extending through said slot into the bore of the shank for engagement with the said helical spring, and a flat spring secured to the stock for engagement in the opening receiving the stock to hold the jaw of the latter normally out of engagement with said shank.

2. A wrench comprising a stock having a jaw removably fitted at one end thereof, a shank having a jaw at one end for coöperation with the jaw of the stock, a strap having openings therethrough for the reception of the stock and the shank, the shank having a longitudinal bore and a longitudinal slot in communication with each other, a yieldable element mounted within the bore of the shank, means detachably connected with the shank at one end of said bore whereby the yieldable element may be inserted in or removed from the bore, a projection carried by the said strap and extending through said slot into the bore of the shank for engagement with the said yieldable element, and means arranged between the stock and the opening receiving the stock to hold the jaw of the latter normally out of engagement with said shank.

In testimony whereof I affix my signature in the presence of two witnesses.

ALBERT LEROY CRITTENDEN.
